UNITED STATES PATENT OFFICE.

TIMOTHY J. COLLINS, OF TOLEDO, OHIO, ASSIGNOR TO RANSOM & RANDOLPH, OF SAME PLACE.

DESIGN FOR A BARBER'S DRESSING-CASE.

SPECIFICATION forming part of Design No. 19,777, dated April 29, 1890.

Application filed April 2, 1890. Serial No. 346,341. Term of patent 3½ years.

To all whom it may concern:

Be it known that I, TIMOTHY J. COLLINS, of Toledo, in the county of Lucas and State of Ohio, have invented and produced a new and original Design for Barbers' Dressing-Cases; and I do hereby declare that the following is a full, clear, and exact description of the invention, which will enable others skilled in the art to which it appertains to make and use the same, reference being had to the accompanying photograph, and to the letters of reference marked thereon, which form part of this specification.

The photograph represents a perspective view of my newly-designed barber's dressing-case.

The leading features of the design consist in a cabinet provided with panel doors A in the lower portion, above which are two drawers B. Immediately above these drawers there is a door C, which, when open, forms a shelf, and above this door there are two drawers D, similar to drawers B. The top E of the cabinet, whose under projecting edges are

trimmed with molding F, is surmounted by a mirror G, the upper portion of the frame of which has a carved ornamentation H the full width. At one side of the cabinet, in line with the back thereof, is a pier-glass I, the frame of which is plain, with the exception of an ornamental carved top. The pier-glass is mounted upon a stand J, the back support of which is an extension e of the cabinet-back, the front support being two legs e', the lower portions of which are turned and their upper portions carved. An ornamental arch a connects the legs, and the top of the stand is plain with beveled edges.

What I claim is—

The design for a barber's dressing-case herein shown and described.

In testimony that I claim the foregoing as my own I hereby affix my signature in presence of two witnesses.

TIMOTHY J. COLLINS.
